(57) **CLAIM**

The ornamental design for a dispenser for hand sanitizer, as
shown and described.

DESCRIPTION

FIG. 1 is a front, perspective view showing our design for a
dispenser for hand sanitizer;

FIG. 2 is a top view thereof;

FIG. 3 is a front view thereof;

FIG. 4 is a left side view thereof;

FIG. 5 is a back view thereof; and,

FIG. 6 is a bottom view thereof.

The broken-line disclosure in the views is understood to
represent a portion of the article in which the claimed design
is embodied, but which forms no part of the claimed design.

1 Claim, 6 Drawing Sheets

FIG. 1

FIG. 2

FIG. 3

FIG. 4

FIG. 5

FIG. 6
